AUTOMATIC FIREARM

Marc Birkigt, Bois-Colombes, France

Application April 16, 1938, Serial No. 202,547
In Belgium February 17, 1938

5 Claims. (Cl. 42—3)

The present invention relates to automatic firearms and especially light guns to be mounted on aircrafts.

The type of gun with which the present invention is concerned includes a breech structure, movable at the rear of the gun tube, under the opposed actions of the recoil produced by each shot and of a counterspring. This breech structure includes two parts adapted to move relatively to each other to a limited extent, one of said parts constituting the breech block proper and the other the firing pin carrier.

A pawl is pivotally carried by the breech block and it is adapted to cooperate with the firing pin carrier in such manner as to interlock these two breech structure elements as long as the breech block has not reached its extreme position toward the front, which corresponds to the closing of the rear end of the gun tube. This pawl is adapted to disconnect these two breech elements when the breech block reaches this extreme position, and simultaneously to lock the breech block in fixed position with respect to the gun casing.

Therefore, when the breech block is thus stopped the firing pin carrier is allowed further to move in the frontward direction under the action of the counterspring, so that the firing pin strikes the cartridge in the known manner.

In some guns of this type, the pawl above mentioned (pivoted to the breech block) cooperates with the other breech element (firing pin carrier) through contacting surfaces which are oblique to the direction of the thrust transmitted from said pawl to said firing pin carrier, and vice versa. Therefore a reaction is produced which has a component tending to move said pawl transversely away from the cooperating surface of the firing pin carrier. This transverse component is without effect as long as the pawl is moving (together with the breech block) along a fixed guiding surface which prevents this transverse movement. But when the breech block reaches its extreme position toward the front, corresponding to the closing of the rear end of the gun tube, said pawl comes opposite an aperture in said guiding surface. Under the effect of the above mentioned component the pawl engages into said aperture, or behind a stop, so that, on the one hand, the breech block and the firing pin carrier are uncoupled, and, on the other hand, the breech block is locked in its extreme front position with respect to the fixed casing of the gun.

In other types of guns, the movement of the pawl which simultaneously produces the uncoupling of the two breech structure elements and the locking of the breech block with respect to the breech casing, instead of being produced by the transverse component above mentioned, is produced by the cooperation of a stop carried in fixed

position by said casing with a corresponding stop carried by the pawl, these two stops coming into contact with each other at the end of the frontward movement of the breech block.

Both of these arrangements have disadvantages.

In guns of the first mentioned type, as the component force which tends to move the pawl transversely exists during the whole movement of the breech structure, it may happen that when the pawl comes opposite the aperture in the fixed casing into which it is to engage under the action of said component force, its transverse displacement is delayed by jamming. This delay may cause the stopping of the operation of the gun or at least a substantial reduction of the number of shots fired per unit of time.

In guns of the second mentioned type, as the two stops provided on the pawl and the casing of the gun strike each other more or less violently, there is a possibility of rebounding of said pawl, which involves serious jolts in the operation of the gun, leading to a rapid wear and tear of the pawl and of the parts cooperating therewith.

The object of the present invention is to provide a gun construction which avoids these various drawbacks.

According to the essential feature of the present invention, I employ simultaneously and in combination, cooperating inclined surfaces on the breech block pawl and the firing pin carrier and cooperating stops carried by said pawl and the fixed breech casing. With such an arrangement, when said pawl is to pass from the position in which it couples the two breech elements together to the position in which it locks the breech block with the breech casing (while simultaneously disengaging said two breech elements from each other) this movement of the pawl is positively controlled by a double action (resulting, on the one hand, from the transverse component of the thrust transmitted from the firing pin carrier to the breech block proper, and on the other hand from the direct action of the stationary stop of the breech casing on the stop carried by the pawl) so that it is possible to make use of one of these actions for starting at the exact time the desired movement of the pawl and of the other action for preventing the rebounding of said pawl.

Other features of the present invention will result from the following detailed description of some specific embodiments thereof.

A preferred embodiment of the present invention will be hereinafter described, with reference to the accompanying drawing, given merely by way of example, and in which:

Fig. 1 is an elevational view, partly in axial vertical section and partly in section on the line I—I of Fig. 3, of the breech mechanism of an

automatic gun for an airplane, made according to the present invention;

Fig. 2 is a view, similar to Fig. 1, showing the same mechanism with another relative position 5 of the parts, corresponding to another period of the operation of the whole;

Fig. 3 is a sectional view on the line III—III of Fig. 1;

Fig. 4 is a vertical section on the line IV—IV 10 of Fig. 1;

Fig. 5 is a partial vertical section on the line V—V of Fig. 1;

Figs. 6 and 7 are detail views showing, on a 15 larger scale, characteristic relative positions of some elements of the structure of Figs. 1 and 2.

In the construction illustrated by the drawing, the barrel or tube 1 of the gun is provided, at its lower end, with a breech casing adapted to accommodate a slidable breech structure. This 20 casing 2 is provided at the top with a cartridge feeding slot 3 and at the bottom with an ejection slot 4 for the cartridge cases.

The breech structure slidable in said casing 2 is urged toward the front position thereof by a 25 counterspring 5. This breech structure includes two main elements 6 and 7, slidably mounted with respect to each other in the direction of the sliding movement of both together in the breech casing.

Breech element 6, which constitutes the breech block proper, serves to force and wedge, through 30 its front end, the cartridge into the gun chamber. When the cartridge is thus fully engaged and held in the gun chamber, the breech block 6 is 35 in its extreme position toward the front, and this position will be hereinafter called "firing position".

As for the other breech element, to wit 7, it carries the firing pin which is to strike the cartridge in the usual manner.

The breech block 6 carries a pawl 13 adapted 40 to couple breech elements 6 and 7 with each other as long as element 6 is not in the firing position. This pawl and element 7 contact each other 45 along surfaces which are so inclined with respect to the direction of the thrust transmitted from the one to the other that the pawl tends to be moved away from element 7 in a transverse direction by the reaction. But a guiding surface 50 along which said pawl is slideable prevents this transverse displacement of the pawl until the end of the forward movement of the whole, when the breech block 6 is reaching its firing position. At the same time, a fixed abutment, 55 carried for instance by casing 2, also moves the pawl into the new position it is to occupy. The combined actions of said fixed abutment and of said cooperating inclined surfaces (of the pawl and the firing pin carrier 7) cause the pawl to be 60 suddenly switched into a position in which it ensures the locking of the breech block 6 with respect to the breech casing 2, while releasing element 7 from said breech block, whereby element 7 is thus allowed to move further under 65 the action of the counterspring 5, although the breech block is now immobilized.

I provide means for driving element 7 in the rearward direction immediately after the firing of a shot, so as to cause it to come back into locking engagement with the breech block 6. This engagement coincides with the disengagement 70 of the breech block 6 from the breech casing 2, and the whole is then moved toward the rear.

From this time on, the pressure of the burnt 75

powder gases on the case of the cartridge that has been fired suffices to ensure the full recoil of the movable breech structure and the ejection of the spent cartridge.

The breech structure constituted by the assembly of the breech block proper 6 and of element 7 is advantageously given an external shape (for instance rectangular as shown by Fig. 5) that it fits in casing 2 in a slidable manner.

Elements 6 and 7 are further mounted relatively to each other in such manner as to permit a slight relative axial displacement of said parts with respect to each other as above explained, elastic means, such as springs r, being advantageously interposed between said elements in 15 such manner as constantly to urge element 7 toward the front end of the fire arm with respect to element 6.

For instance, as shown by the drawing, element 7 is so designed as to surround at least 20 partly the breech block, said element 7 being provided, at the front end thereof, with a cross member 9 the central part of which carries a plug 10 the front part of which is fitted with the firing pin 8. The counterspring 5 above mentioned, which is housed in an axial cavity 11 of the breech block 6, bears upon the rear face of said plug 10, so as to push it forwardly.

The breech block 6 is provided with a transverse slot 12, elongated in the axial direction of 30 the firearm, so as to be longer than the longitudinal section of cross member 9. The limited displacement between elements 6 and 7 results from the difference of size between said member and said slot, or, in other words, from the play 35 of member 9 in slot 12.

The side walls of element 7 are further provided with housings 7' for the springs r above mentioned, each of said springs being interposed between one end of the corresponding slot 7' and 40 a corresponding lug b rigid with the breech block 6 and adapted to slide in said slot 7' when elements 6 and 7 of the breech structure move with respect to each other.

In this embodiment of my invention, the locking means above described in a general manner 45 are made as follows:

The pawl 13 above referred to is pivoted, at its front end, to the breech block 6, and its rear end is provided with a head 14.

The breech casing 2 is provided with an aperture or notch 15 into which said head 14 can engage when the breech block 6 reaches its firing position. The contacting faces 14' and 15' of said head and said notch respectively are, for 55 instance, such that a thrust in the rearward direction exerted by the breech block on the breech casing cannot cause the head 14 to disengage itself from notch 15. For this purpose, said cooperating faces 14' and 15' are given the 60 proper inclination with respect to the direction of the thrust (see Figs. 1 and 2).

Pawl 13 and element 7 are provided with cooperating inclined surfaces, such as 16 and 17, adapted, when element 7 is moving in the rearward 65 direction with respect to the breech block 6, of causing head 14 to be disengaged from notch 15.

I provide, on element 7, a surface 18 adapted to prevent head 14 from leaving notch 15 as long as element 7 is in front position with respect to 70 the breech block 6, said surface 18 cooperating with the top edge of a notch provided in head 14.

Pawl 13 and the breech casing 2 are provided with respective inclined surfaces 20 and 21 adapted to cooperate with each other in such 75

manner that, when the whole of elements 6 and 7 is moving toward the front, near the end of this displacement, these cooperating surfaces bring pawl 13 into a position, hereinafter called 5 "lower position", in which head 14 is disengaged from the notch 19 of element 7 and on the contrary engaged into notch 15, inclined surface 20 being preferably mounted laterally on pawl 13.

In accordance with the principle of the present 10 invention, the movement of pawl 13 into engagement with notch 15 (from the position of Fig. 7 into the position of Fig. 6) instead of being started merely by the cooperation of inclined surfaces 20 and 21 (carried by the head of the 15 pawl and by the breech casing), is also produced as a consequence of the thrust transmitted by element 7 to the breech block 6 through pawl 13.

Consequently, head 14 and the inner wall of notch 19 are provided with respective inclined 20 surfaces 14'' and 19'' adapted to cooperate with each other so that near the end of the return stroke of the whole of the movable breech structure toward the front, the thrust transmitted from one of said inclined surfaces to the other 25 produces a transverse component, corresponding to the downwardly directed force F, which tends to push head 14 into notch 15 as soon as said head comes opposite said notch.

Thus, as soon as, in the course of the frontward movement of the whole of the breech structure, said head 14 is brought above notch 15, it is driven into said notch by the combined action of cooperating inclined surfaces 20 and 21 on the one hand and cooperating inclined surfaces 14'' 35 and 19'' on the other hand. In some cases, surfaces 14'' and 19'' may start the downward pivoting movement of pawl 13 before inclined surfaces 20 and 21 have come into contact with each other.

40 It should be noted that springs 7 also transmit to pawl 13, through inclined surfaces 14'' and 19'', an effort in the same direction as F.

The system above described is both simple and efficient. I may also, with advantage, as 45 shown by the drawing, give the breech block 6 a cross section in the form of an inverted T, the vertical branch of which extends between the branches of element 7, which is substantially fork-shaped.

50 In this case, I may, as shown by the drawing, provide a pawl 13 in each of the horizontal branches of the T. The corresponding notches 19 are formed in the under edges of forked shaped element 7 and notches 15 are provided in the 55 bottom wall of casing 2, immediately behind aperture 4.

Whatever be the specific arrangement that is chosen, such a system has the advantage that, when the head 14 of pawl 13 comes opposite notch 50 15 it is caught between two inclined surfaces 21 and 19'', both of which are adapted to act on said head 14 for driving it into notch 15, so that this movement of head 14 is obtained more quickly and more safely than if it were subjected to the 65 mere action of a single inclined surface or abutment.

Finally, the means for moving the breech structure in the rearward direction after the firing of a shot are so devised that element 7 is 70 first moved toward the rear with respect to the breech block 6 so as to come back into engagement therewith. Then the cooperation of inclined surfaces 16 and 17 causes pawl 13 to be brought back into the upper position, where it locks elements 6 and 7 together. The rearward

movement of the whole is then ensured either by the means which have already produced the separate rearward movement of element 7 or, more simply and as it will be hereinafter supposed, under the effect of the pressure of the burnt powder gases transmitted through the metal rear end of the spent cartridge.

In the example shown by the drawing, the means which start the rearward movement of element 7 so as to bring it back into engagement 10 with element 6 consist of a piston and cylinder system 20-25 operated by the burnt powder gases present in the bore of the gun tube as soon as the projectile has travelled a certain distance inside said bore and thus uncovered an orifice 27.

With such an arrangement, immediately upon the shot being fired, element 7 is pushed toward the rear through the movable element of said piston and cylinder system. Then pawl 13 unlocks element 7 from with casing 2 and couples elements 6 and 7 together, the whole being caused to recoil by the action of the burnt powder gases.

This rearward movement of the whole of the movable breech structure under the effect of the pressure of the burnt powder gases compresses counterspring 5, which subsequently brings back the whole toward the front for the next shot.

In a general manner, while I have, in the above description, disclosed what I deem to be practical and efficient embodiments of the present invention, it should be well understood that I do not wish to be limited thereto as there might be changes made in the arrangement, disposition, and form of the parts without departing from the principle of the present invention as 30 comprehended within the scope of the accompanying claims.

What I claim is:

1. An automatic firearm which comprises, in combination, a tube, a breech structure movable with a reciprocating motion in line with said tube at the rear thereof, a stationary casing rigid with said tube for guiding said breech structure, said breech structure including a breech block proper and a firing pin carrier movable longitudinally to a limited extent with respect to said breech block, a pawl movably carried by said breech block, said firing pin carrier being provided with a notch adapted to cooperate with said pawl for interlocking said breech block and said firing pin carrier, the contacting surfaces of said pawl and said firing pin carrier being so inclined with respect to each other and with respect to the direction of thrust as to produce a transverse component which tends to move said pawl transversely away from said notch, a guiding surface in said casing adapted to keep said pawl in said notch as long as said breech block has not reached the end of its frontward stroke, said guiding surface being provided with a notch 40 adapted to receive said pawl pushed therein by the action of said component, and cooperating projections carried by said casing and said pawl respectively for driving said pawl away from the first mentioned notch and into the second mentioned notch when said breech block reaches the end of its frontward stroke.

2. An automatic firearm which comprises, in combination, a tube, a breech structure movable with a reciprocating motion in line with said tube at the rear thereof, a stationary casing rigid with said tube for guiding said breech structure, said breech structure including a breech block proper and a firing pin carrier movable longitudinally to a limited extent with respect to said breech 70

block, a pawl movably carried by said breech block, said firing pin carrier being provided with a notch adapted to cooperate with said pawl for interlocking said breech block and said firing pin carrier, the contacting surfaces of said pawl and said firing pin carrier being so inclined with respect to each other and with respect to the direction of thrust as to produce a transverse component which tends to move said pawl transversely away from said notch, a guiding surface carried by said casing arranged to keep said pawl in said notch as long as said breech block has not reached the end of its frontward stroke, said guiding surface being provided with a notch adapted to receive said pawl pushed therein by the action of said component, cooperating projections carried by said casing and said pawl respectively for driving said pawl away from the first mentioned notch and into the second mentioned notch when said breech block reaches the end of its frontward stroke, thereby said pin carrier is disengaged from with said breech block and can further move forward, a counterspring for urging said firing pin carrier in the frontward direction, and means for returning said pawl to said first mentioned notch comprising a projection carried by said pawl adapted to remain engaged in the first mentioned notch after the disengagement of said firing pin carrier and said breech block, and a projection carried by the front wall of the first mentioned notch adapted to cooperate with the last mentioned projection of said pawl, said projections, pawl, firing pin carrier, breech block, and notches being so adapted and arranged as to move said pawl out from the second mentioned notch and into the first mentioned notch at the beginning of the return movement of said fire pin carrier whereby to release said breech block from said casing and simultaneously to interlock said breech block and said firing pin carrier.

3. An automatic firearm which comprises, in combination, a tube, a breech structure, movable with a reciprocating motion in line with said tube at the rear thereof, a stationary casing rigid with said tube for guiding said breech structure, said breech structure including a breech block proper and a firing pin carrier movable longitudinally to a limited extent with respect to said breech block, a pawl movably carried by said breech block, said firing pin carrier being provided with a notch adapted to cooperate with said pawl for interlocking said breech block and said firing pin carrier, the contacting surfaces of said pawl and said firing pin carrier being so inclined with respect to each other with respect to the direction of thrust as to produce a transverse component which tends to move said pawl transversely away from said notch, a part carried by said casing having a guiding surface for said pawl arranged to keep it engaged in said notch as long as said breech block has not reached the end of its frontward stroke, said guiding surface being provided with a notch adapted to receive said pawl pushed therein by the action of said component, cooperating projections carried by said casing and said pawl respectively said projections being so adapted and arranged as to drive said pawl out from the first mentioned notch and into the second mentioned notch when said breech block reaches the end of its frontward stroke, whereby said firing pin carrier is disengaged from with said breech block, said firing pin carrier being so arranged with respect to said breech block and said casing that it is free to continue movement in the frontward direction when disengaged from the breech block and whereas said breech block is locked in firing position with respect to said casing, a counterspring for urging said firing pin carrier in the frontward direction, and means comprising cooperating surfaces on said firing pin carrier and said catch, said surface being so arranged with respect to the firing pin carrier and catch as to keep said pawl engaged in the second mentioned notch in locked position with respect to said casing during the displacement of said firing pin carrier subsequent to the locking of said breech block.

block and can further move forward, a counter-spring for urging said firing pin carrier in the frontward direction, and means, operative by the powder gases, from the gun tube, said means being so adapted and arranged as to drive back said firing pin carrier toward said breech block immediately after the firing of a shot in said gun, said means comprising a projection carried by said pawl adapted to remain engaged in the first mentioned notch after the disengagement of said firing pin carrier from with said breech block, and a projection carried by the front inner wall of the first mentioned notch adapted to cooperate with the last mentioned projection of said pawl for moving said pawl out from the second mentioned notch and into the first mentioned notch at the beginning of the return movement of said firing pin carrier.

4. An automatic firearm according to claim 3 further including elastic means for urging said fire pin carrier frontwardly with respect to said breech block.

5. An automatic firearm which comprises, in combination, a tube, a breech structure movable with a reciprocating motion in line with said tube at the rear thereof, a stationary casing rigid with said tube for guiding said breech structure, said breech structure including a breech block proper and a firing pin carrier movable longitudinally to a limited extent with respect to said breech block, a pawl movably carried by said breech block, said firing pin carrier being provided with a notch adapted to cooperate with the last mentioned projection of said pawl, said projections, pawl, firing pin carrier, breech block, and notches being so inclined with respect to each other and with respect to the direction of thrust as to produce a transverse component force which tends to move said pawl transversely out from said notch, a part carried by said casing having a guiding surface for said pawl arranged to keep it engaged in said notch as long as said breech block has not reached the end of its frontward stroke, said guiding surface being provided with a notch adapted to receive said pawl pushed therein by the action of said component force, cooperating projections carried by said casing and said pawl respectively said projections being so adapted and arranged as to drive said pawl out from the first mentioned notch and into the second mentioned notch when said breech block reaches the end of its frontward stroke, whereby said firing pin carrier is disengaged from with said breech block, said firing pin carrier being so arranged with respect to said breech block and said casing that it is free to continue movement in the frontward direction when disengaged from the breech block and whereas said breech block is locked in firing position with respect to said casing, a counterspring for urging said firing pin carrier in the frontward direction, and means comprising cooperating surfaces on said firing pin carrier and said catch, said surface being so arranged with respect to the firing pin carrier and catch as to keep said pawl engaged in the second mentioned notch in locked position with respect to said casing during the displacement of said firing pin carrier subsequent to the locking of said breech block.

MARC BIRKIGT.
